UNITED STATES PATENT OFFICE

2,403,522

STRIKER TOY

William V. Goldstein, Freehold, and Lou Shooman, Belmar, N. J.

Application May 11, 1944, Serial No. 535,018

1 Claim. (Cl. 124—4)

1

An object of our invention is a toy which is actuated by strokes with a hammer and which, therefore, is adapted to develop physical strength and skill of a child in a playful and amusing way.

Another object is a toy of this kind which shows a plurality of spots, each of which may be selected for the stroke, and which, therefore, is adapted to develop discriminating and counting abilities.

Further objects are a toy of this kind which is ready for further strokes immediately after each stroke, and a toy which is provided with movable members that move in one direction when hit by the hammer and can be moved back in the opposite direction by a subsequent stroke.

Still other objects are to provide such a toy with movable members which are adapted to project a body away or into the air, and to provide recesses in the surface of such members for the reception of such bodies.

Still further objects and advantages will appear from the following description of an exemplifying embodiment of our invention and of certain modifications thereof, from the appended claim and from the accompanying drawing in which:

Fig. 1 shows a vertical cross-section of an illustrative embodiment of the invention, said cross-section being taken along the line 1—1 in Fig. 3.

Fig. 2 shows another vertical cross-section of the same embodiment, said latter cross-section being taken along the line 2—2 in Fig. 3.

Fig. 3 shows the same embodiment seen from the upper side.

Fig. 4 shows a vertical side view of a modification of a part used in said embodiment.

Figs. 5, 6, 7 and 8 show different modifications of another part used in the same embodiment, Fig. 5 and Fig. 6 being perspective views, Fig. 7 being a vertical side view and Fig. 8 being a vertical central cross-section. Figs. 5, 6, 7 and 8 are represented on a larger scale than Figs. 1, 2, 3 and 4.

Referring to the drawing, numeral 1 indicates a casing having a rectangular inner space surrounded by walls. The walls may be permanently closed after assemblage of the toy's parts, for example by glue; or known and conventional means for opening the casing may be provided.

An axle or shaft 2 extends horizontally throughout the length of the casing 1. Three members 3, 4 and 5 are rotatably mounted on the shaft 2 and are spaced from each other by cylindrical parts 6 and from the walls of the casing by cylindrical parts 7, the parts 6 and 7 having bores 55

through which the shaft 2 passes. In Figs. 1, 2, and 3, the members 3, 4, 5 are circular disks, the upper section of each circle being cut off. The members 4 and 5 are shown with the cut off edge positioned horizontally. The member 3 is shown in a tilted position. The lower rim of said disks engages frictionally the lower or bottom wall of the casing 1. This, however, is not indispensable. These members may engage the side walls frictionally or may not contact any of the walls. For example, each of said members may be replaced by a lever 8 shown in Fig. 4.

A number of posts or cylindrical pieces 9 are inserted vertically in holes passing through the upper wall or platform of the casing 1. These posts are slideable in the holes frictionally, the friction being sufficiently slight to be overcome when the upper end of the post is hit by a hammer. The posts 9 are arranged in pairs, each pair comprising posts positioned vertically over the two ends of the upper edge of the same member 3, 4 or 5.

Each post 9 may be replaced by one of the modifications shown in Figs. 5, 6, 7 and 8. For example, a slotted piece 10 may be used. Preferably, the piece 10 has a slot 11 positioned in a vertical central plane of the piece, extending from the upper end surface and ending at a small distance from the lower end surface, and has a second slot positioned in a plane perpendicular to said first plane, extending from the lower surface and ending at a small distance from the upper surface. These slots make the post more resilient and facilitate the proper frictional contact with the wall of the respective hole.

The cross-sections of the posts 9 are preferably circular. But posts of other cross-sections may be used, for example, posts 13 having square cross-sections.

The post 14 is a modification having a head 15 affixed to its upper end. The upper surface of the post or of the head 15 may have a recess 16 adapted to support a ball 21 or any other throwable object which will leap when the post is pushed upward.

The post 17 has a hollow space with a mouth or entrance at the upper surface of the post. The space, 18, is adapted to receive a body which will leap when the post is pushed upward. For example, this body may be a little doll or figure 19 equipped with a parachute 20 which will unfold and spread when the doll 19 starts falling after the upward leap. The doll 19 and the parachute 20 are shown in this latter condition in Fig. 8.

3

All parts of the toy may be made of wood or of any other suitable material. The individual posts may be distinguished from each other by numbers or colors whereby the educational value of the toy is increased.

The toy operates as follows: When the upper surface of one of the posts 9 is hit by the stroke of a hammer or the like, the lower end of this post pushes one side of the corresponding member 3, 4 or 5 down whereby the other side of the same member is turned up and the other post 9 of the same pair is pushed upward. This movement makes any body that is supported by said latter post leap or spring in upward direction.

We desire it understood that our invention is not confined to the particular embodiment and the modifications thereof shown and described and that the invention may be carried out in other ways without departing from the spirit of the invention as it is obvious that the particular

embodiment shown and described is only one of the many that may be employed to attain the objects of our invention.

Having described the nature of our invention and how it operates, what we claim and desire to secure by Letters Patent is:

A toy comprising a casing having a platform and two holes in said platform, a post inserted in one of said holes and another post inserted in the other hole, said posts being frictionally slidable in said holes, and a member positioned below said platform, connected to said casing turnably around an axis parallel to said platform, and having the shape of a disk of which a segment is cut off whereby the circumference of said member consists of an arc and of a chord-like positioned surface, said latter surface contacting the lower ends of said posts.

WILLIAM V. GOLDSTEIN.
LOU SHOOMAN.
